[57] ABSTRACT

This invention relates to an improved coal charging car, adapted for delivering coal to the charging holes of a coke oven battery for conversion of coal to coke. This coal charging car includes: a coal hopper assembly, a turntable assembly, a lid lifter assembly and a coal drop assembly. The coal hopper and turntable assemblies are displaced from the charging hole when coal is being deposited in the charging hole to avoid exposure of these assemblies to the heat from the charging hole. A heat insulation layer is provided and is disposed between the turntable assembly and the coal hopper assembly for the purpose of insulating the turntable assembly from the extreme heat emanating from the coke oven during the time when coal is being charged into the charging hole of the coke oven. A support is provided for the turntable platform and the support extends substantially under the entire turntable platform to provide more complete support of the turntable platform and to reduce warpage of the turntable platform. An air intake pipe is provided which cools the oil in the speed reducer and maintains the cleanliness of the speed reducer.

AUTOMATIC COAL CHARGING CAR

BACKGROUND OF THE INVENTION

This invention relates to an improved coal charging car adapted for delivering coal to at least one coke oven. The coal charging car of this invention may be used with a variety of coke ovens for the conversion of coal to coke by carbonization. An example of the coking plant and process in which the coal charging car of this invention may be used is described in the Encyclopedia of Chemical Technology, edited by R. E. Kirk and D. F. Othmer, Volume 3, pages 160 - 167 (1954 edition).

U.S. Pat. Nos. 3,672,519 and 3,675,797 to Pries and 15 2,448,953 to L. Wilputte et al, disclose charging cars for coke ovens which differ in design from the coal charging car of this invention.

SUMMARY OF THE INVENTION

The coal charging car of this invention is adapted to 20 convey coal automatically from a coal supply source to at least one coke oven, by lifting at least one lid from a charging hole on the coke oven and delivering or "charging" coal through the charging hole into the coke oven. In normal operation, the charging hole has heat emanating from it when the coke oven is in operation. The coal charging car in combination includes at least one, and preferably three, of each of the following assemblies: a coal hopper assembly, a turntable assembly, a lid lifter assembly, and a coal drop assembly.

The coal hopper assembly receives coal from a coal supply source, such as a coal bin. A turntable assembly is disposed below each coal hopper assembly and is adapted to dispense coal from the coal hopper assembly in a uniform flow. A lid lifter assembly is disposed adjacent to each coal hopper assembly. The lid lifter assembly is adapted to clean the lid of a coke oven, lift the lid up and off the charging hole of the coke oven, swing the lid out of the way prior to charging coal into the charging hole of the coke oven and replace and seat the lid on the charging hole of the coke oven after charging has been completed. A coal drop assembly is connected to and disposed below each coal hopper assembly. The coal drop assembly delivers coal from the coal hopper assembly to the charging hole of the coke oven and conducts coal gases away from the charging hole of the coke oven.

The coal charging car of this invention is an improved design of previous coal charging cars and includes the following features which are among the features which distinguish it from previous coal charging cars. The coal hopper assembly and the turntable assembly are displaced from and out of alignment with the charging hole of the coke oven when coal is being charged into the charging hole, thereby avoiding direct exposure of the coal hopper assembly and the turntable assembly to the heat from the charging hole. In the preferred embodiment, a heat insulation layer is provided and is disposed between the turntable assembly and the coal hopper assembly for the purpose of insulating the turntable assembly from the extreme heat emanating from the coke oven during the time when coal is being charged into the charging hole of the coke oven. In the preferred embodiment, a support is provided for the turntable platform and the support extends substantially under the entire turntable platform to provide more complete support of the turntable platform and

to reduce warpage of the turntable platform. In the preferred embodiment, an air intake pipe is provided which cools the oil in the speed reducer and maintains the cleanliness of the speed reducer. As a result of these and other improvements described subsequently, the coal charging car of this invention operates more efficiently and more effectively than coal charging cars known in the prior art and operates with less wear and damage to the coal charging car.

DESCRIPTION OF THE DRAWINGS

FIG. 1 is an isometric view of a coal charging car according to this invention mounted on a battery of coke ovens.

FIG. 2 is a front elevational view of the coal charging car, viewed from the direction shown by arrow 2 in FIG. 1.

FIG. 3 is a top view of FIG. 2.

FIG. 4 is a side view of FIG. 2.

FIG. 5 is a top plan view of one turntable assembly used in the coal charging car shown in FIG. 2.

FIG. 6 is a vertical section of FIG. 5 along the lines 6-6.

FIG. 7 is a side view of FIG. 5 along the lines 7-7.

FIG. 8 is a top plan view of the deflector positioned within the coal hopper assembly.

FIG. 9 is a side view of FIG. 8.

FIG. 10 is a side elevational view of one lid lifter assembly which is used in the coal charging car shown in FIG. 2.

FIG. 11 is a top plan view of the lid lifter assembly shown in FIG. 10.

FIG. 12 is an enlarged vertical section of FIG. 11 along the lines 12-12.

FIG. 13 is a horizontal section of FIG. 10 along the lines 13-13.

FIG. 14 is an enlarged vertical section of FIG. 11 along the lines 14-14.

FIG. 15 is an enlarged vertical section of FIG. 11 along the lines 15-15.

FIG. 16 is an enlarged vertical section of FIG. 11 along the lines 16-16.

FIG. 17 is an enlarged vertical section of FIG. 11 along the lines 17-17.

FIG. 18 is a top plan view of three lid lifter assemblies which are used in the coal charging car shown in FIG. 2.

FIG. 19 is an enlarged view of one coal drop assembly which is used in the coal charging car shown in FIG. 4.

FIG. 20 is a disassembled view of part of the coal drop assembly shown in FIG. 19.

FIG. 21 is an enlarged view of one coal drop assembly which is used in the coal charging car shown in FIG. 2.

FIG. 22 is an enlarged view of a portion of FIG. 19.

DETAILED DESCRIPTION

Introduction

Referring to FIG. 1, the coal charging car of this invention is indicated generally by the numeral 1. The coal charging car 1 is adapted to be mounted on the roof 4 of a battery of coke ovens. The battery of coke ovens is indicated generally by the numeral 5 and comprises a plurality of coke ovens 8. In the embodiment shown in FIG. 1, each coke oven is approximately 16 feet 8 inches high, 47 feet 1 1/4 inches long and 1 foot 5 1/2

inches wide. The roof 4 of the coke oven battery 5 is a horizontal plane and, as a result of additional support structure under the coke oven battery 5, the roof 4 is approximately 30 feet above the ground.

In the battery 5 of coke ovens 8, each coke oven 8 has three charging holes 9 disposed on the roof 4 of the battery 5 of coke ovens 8. The coal charging car 1 of this invention is disposed on the roof 4 and is adapted for conveying a volumetrically controlled amount of coal to the coke ovens 8 by lifting a lid on each charging hole 9 and depositing or "charging" coal in the charging hole 9. Other batteries 5 of coke ovens 8 may have a greater or lesser number of charging holes 9.

In typical operation, the coal charging car 1 delivers coal either sequentially or simultaneously into the three charging holes 9 of one coke oven 8. Then, the charging car 1 moves in a horizontal direction on rails 18 which form a track and which guide the charging car 1 to a coal supply source, such as a coal bin (not shown). After obtaining another supply of coal, the charging car 1 moves to the next coke oven 8 to repeat the operation of delivering or "charging" coal into the next group of three charging holes 9. It is possible to operate the charging car 1 to charge into each of the three charging holes 9 separately, known as sequential charging, or to charge all three charging holes of one coke oven 8 in unison, known as simultaneous charging. The next coke oven 8 to be charged may be adjacent to the previous coke oven 8 charged or it may be any other coke oven 8 in the battery 5.

Each coke oven 8 has an exhaust standpipe 16 disposed on the roof 4 over the coke oven 8 for the purpose of aspirating and conducting coal gases out of the coke oven 8. The embodiment shown in FIG. 1 illustrates nine coke ovens 8, but a coke oven battery 5 may comprise more than nine coke ovens or less than nine coke ovens. For purposes of clarity and simplification, FIG. 1 does not show an exhaust standpipe 16 for each coke oven 8, although normally each coke oven 8 has an exhaust standpipe 16.

Referring to FIGS. 1, 2, 3, and 4, the coal charging car 1 includes the following major assemblies: at least one coal hopper assembly, referred to generally by the numeral 20, at least one turntable assembly, referred to generally by the numeral 22, at least one lid lifter assembly, referred to generally by the numeral 24, and at least one coal drop assembly, referred to generally by the numeral 26. There are three of each of the foregoing assemblies because there are three coal charging holes 9 for each coke oven 8. Preferably, the number of the foregoing major assemblies is equal to the number of coal charging holes 9 for each coke oven 8. Thus, if each coke oven 8 has four coal charging holes 9, the coal charging car 1 might be arranged with four of the foregoing major assemblies. Similarly, if each coke oven 8 had two coal charging holes 9, then the coal charging car 1 might be arranged to have two of the foregoing major assemblies. In summary, the coal charging car 1 may comprise one of each of the foregoing major assemblies or a plurality of each of the foregoing major assemblies.

The coal hopper assembly 20 receives coal from a coal supply source, such as a coal bin (not shown), by means of a bin gate 23 and a bin gate operator 25. Referring to FIGS. 4 and 19, the coal hopper assembly 20 has a discharge spout 28 at the bottom of the coal hopper assembly 20 adjacent to the coal drop assembly

26 at the place where the upper end of the coal drop assembly 26 is connected to the coal hopper assembly 20. The coal from the coal hopper assembly 20 passes through the discharge spout 28 on its way to the charging hole 9, shown in FIG. 1. The turntable assembly 22 is adapted to dispense coal at a uniform rate from the coal hopper assembly 20 to the coal drop assembly 26. Referring to FIG. 4, the discharge spout 28, the coal hopper assembly 20 and the turntable assembly 22 are not positioned directly over the charging hole 9, shown in FIG. 1, but instead are displaced from, that is, positioned out of alignment with the charging hole 9, shown in FIG. 1, when coal is being charged into the charging hole 9. This displacement avoids exposure of the turntable assembly 22 to heat emanating from the charging hole 9. This heat is the result of the high temperature in the coke oven 8 when the coke oven 8 is in operation. The coal is carbonized within the coke ovens 8 at a temperature which is commonly in the range of from 1800° to 2200°F.

The lid lifter assembly 24 is disposed adjacent and under the coal drop assembly 26, the coal hopper assembly 20 and the turntable assembly 22. The lid lifter assembly 24 is adapted to move under the coal drop assembly 26 to clean the lid 29 covering the charging hole 9, lift and swing the lid 29 out of the way prior to the charging of coal into the charging hole 9 of the coke oven 8 and replace and seat the lid 29 on the charging hole 9 of the coke oven after such charging. The coal drop assembly 26 is connected to and disposed below the coal hopper assembly 20. The coal drop assembly 26 is disposed adjacent to and predominantly below the turntable assembly 22 and slightly higher than the lid lifter assembly 24. The coal drop assembly 26 is adapted to deliver coal from the coal hopper assembly 20 to the charging hole 9 of a coke oven 8, shown in FIG. 1, and to conduct coal gases away from the charging hole 9 of the coke oven 8. Referring to FIG. 4, the displacement of the coal hopper assembly 20 and the turntable assembly 22 is the result of an inclined coal section 200 of the coal drop assembly 26. The inclined coal section 200 is described in detail subsequently.

COAL HOPPER ASSEMBLY

Referring to FIGS. 2, 3, 4, 5, 7 and 19, the coal hopper assembly 20 includes a coal hopper 30, a discharge spout 28, a deflector 48, and a coal guide 34, none of which rotate.

The coal hopper 30 is a large container which functions as a receptacle for the purpose of receiving coal from a coal source (not shown) and as an intermediate storage reservoir for the purpose of holding coal until the coal is ready to be delivered to a charging hole of a coke oven. Referring to FIGS. 2 and 4, the coal hopper 30 has a substantially circular shape at its upper portion, referred to generally by the numeral 36, and a partial funnel shape at its bottom portion, referred to generally by the numeral 38. Referring to the view in FIG. 6, the lower portion 38 of the coal hopper 30 has an inclined side 40 and a substantially vertical side 42. Referring to the view in FIG. 7, two other sides 44 and 46 of the lower portion 38 of the coal hopper 30 are inclined. The combination of the substantially vertical side 40 and the three inclined sides 42, 44 and 46 give the lower portion 38 of the coal hopper 30 its partial funnel shape.

Referring to FIG. 19, the discharge spout 28 is located at the bottom of the coal hopper 30 and is positioned at one side of the coal hopper 30 adjacent to the coal drop assembly 26. The discharge spout 28 is connected to the coal drop assembly 26 and is adapted to pass coal from the coal hopper 30 to the coal drop assembly 26.

Referring to FIGS. 6, 7, 8, 9 and 19, the deflector 48 is disposed in approximately the bottom half of the coal hopper 30 and occupies approximately one-quarter of the area in the bottom half of the coal hopper 30. The deflector 48 is adapted to deflect coal from the coal hopper 30 into the discharge spout 28. Referring to FIGS. 8 and 9, the deflector 48 includes: two flat plates 50 and 52, arranged at about a 90° right angle to one another, and a curved plate 54. The two flat plates 50 and 52 each have a straight substantially vertical edge 56, a straight substantially horizontal edge 57 and a curved edge 58 and 60. As a result, the two flat plates 50 and 52 each have the approximate shape of a quarter circle, but with the vertical edges 56 being slightly longer than the horizontal edges 57. The straight vertical edges 56 are joined to one another at the right angle. The curved plate 54 is a shell-like structure having a shape similar to that of a one-eighth section of an orange peel. The curved plate 54 has a curved bottom edge 62 and curved side edges. Each curved side edge of the curved plate 54 is joined to the curved edge 58 and 60 of one of the flat plates. As a result, the deflector 48 is enclosed on all three of its upstanding sides by plates 50, 52 and 54, except for a passageway 64 in one of the substantially vertical plates 50. Coal is fed from the coal hopper assembly 20 through the passageway 64 into the deflector 48 and then into the discharge spout 28.

Referring to FIGS. 6 and 7, the coal guide 34 is disposed within the coal hopper assembly 20, at the bottom of the coal hopper 30, approximately centered over the turntable assembly 22. The coal guide 34 is adapted to cooperate with the turntable assembly 22 in guiding coal on to the turntable platform 82 of the turntable assembly 22. The coal guide 34 is a large, dish-shaped, substantially circular, partially funnel shaped, structure having an open bottom. The upper periphery of the coal guide 34 is partially funnel-shaped, the middle periphery is irregularly funnel-shaped; and the lower periphery is substantially circular. The partially funnel shape of the upper periphery is the result of the following configuration. Referring to the view in FIG. 6, the upper periphery has an inclined side 66 and a substantially vertical side 67. Referring to the view in FIG. 7, the upper periphery has two inclined sides 68 and 69. The incline of sides 68 and 69 more closely approaches the vertical plane than does inclined side 66. Referring to FIG. 6, since side 67 is substantially vertical, the upper periphery does not have a completely funnel shape, but only a partial and irregular funnel shape.

The irregular funnel shape of the middle periphery is the result of the following configuration. Referring to the view in FIG. 6, the middle periphery has an inclined side 72 and an inclined side 73. The incline of side 73 more closely approaches the vertical plane than does the incline of side 72. Referring to the view in FIG. 7, the middle periphery has an inclined side 74 and an inclined side 75. Referring to FIGS. 6 and 7, since the incline of side 72 is different from the similar incline of

sides 73, 74 and 75, the funnel shape of the middle periphery is irregular. The shape of the upper periphery and the middle periphery of coal guide 34 is consistent with the shape of coal hopper 30 having inclined side 40 and substantially vertical side 42. The sides 66, 67, 68 and 69 of the upper periphery of the coal guide 34 are affixed to the side walls 40, 42, 44 and 46 of the coal hopper 30. Referring to FIGS. 6 and 7, the lower periphery of the coal guide 34 is defined by sides 80 which are substantially vertical and circular in configuration. The coal guide 34 provides a transition between the non-rotating coal hopper assembly 20 and the rotating turntable assembly 22. A heat insulation layer 79 is maintained in the lower periphery of the coal guide 34, defined by the sides 80 of the coal guide 34. This insulation layer 79 is adapted to insulate the turntable assembly 22 from the heat emanating from the coke oven 8. Preferably, the head insulation layer 79 is a bed of coal and is approximately 3 inches in depth.

Referring to FIG. 4, the coal hopper assembly further includes a volumetric control 78 which controls the volume of coal received by the coal hopper assembly 20 from the coal source (not shown).

Turn Table Assembly

Referring to FIGS. 5, 6, and 7, the turntable assembly 22 includes a rotating turntable platform 82 and a rotating turntable support 84. The turntable platform 82 is a large, substantially flat plate, which is substantially circular in shape, and approximately centered beneath the coal hopper assembly 20. The turntable support 84 is approximately centered below the turntable platform 82 and supports the turntable platform 82. The turntable support 84 is substantially circular in shape and the diameter of the turntable support 84 approaches the diameter of the turntable platform 82, but is slightly less than the diameter of the turntable platform 82. The turntable support 84 extends substantially under the entire turntable platform 82 to provide substantially complete support to the turntable platform 82 and to reduce warpage of the turntable platform 82. Such warpage might otherwise occur as a result of heat emanating from the coal charging hole 9 and the load forces resulting from the weight of the coal in the coal hopper assembly 20. Referring to FIGS. 6 and 19, the turntable platform 82 and the turntable support 84 are disposed at the bottom of the coal hopper 30 and are adapted to rotate to dispense coal from the coal hopper 30 through the discharge spout 28 to the coal drop assembly 26.

Referring to FIGS. 4, 6 and 7, the turntable assembly 22 further includes a drive motor 86, a speed reducer 88 and a support coupling 90. Optionally, the support coupling 90 may be made in two sections 91 and 92 for convenience. The drive motor 86 is adapted to supply rotating power to rotate the turntable platform 82. The speed reducer 88 is cooled by oil, is connected to the drive motor 86 and is adapted to reduce the speed of the rotating power supplied from the drive motor 86. The support coupling 90 and the speed reducer 88 are disposed directly beneath and connected to the turntable support 84. The support coupling 90 is adapted to transmit power from the speed reducer 88 to the turntable support 84 to rotate the turntable platform 82. Referring to FIG. 4, as a result of the inclined coal section 200 of the coal drop assembly 26, the coal drop assembly 26 is not directly under the coal hopper assem-

bly 20, but is displaced therefrom. There is room under the coal hopper assembly 20 so that the turntable drive elements, that is, the drive motor 86 and the speed reducer, may be arranged right side up and under the turntable assembly 22. This arrangement facilitates ease of maintenance of the drive motor 86 and the speed reducer 88.

Referring to FIG. 5, the turntable assembly 22 further includes a plurality of coal ribs 94 and a plurality of coal ties 95. The coal ribs 94 are elongated members affixed to the top surface of the turntable platform 82. The coal ribs 94 are each positioned on a radius of the turntable platform 82 and are equally spaced apart from one another. The coal ribs 94 need not extend completely to the center of the turntable platform 82, nor to the outer periphery of the turntable platform 82. The coal ribs 94 are adapted to rotate with the turntable platform 82 and assist in moving the coal from the coal guide 34 into the deflector 48 and through the discharge spout 28. The coal ties 95 are elongated structural members affixed to the top surface of the turntable platform 82 to brace the coal ribs 94 in position. The coal ties 95 are positioned near the outer circumference of the turntable platform 82 and extend between adjacent coal ribs 94 near the outer ends of the coal ribs 94. There is one coal tie 95 between each pair of coal ribs 94. This embodiment uses 10 coal ribs 94 and ten coal ties 95. Other embodiments may use as few as five or as many as 20 coal ribs 94 and coal ties 95.

Referring to FIGS. 6 and 7, the turntable assembly further includes a turntable housing 98. The turntable housing 98 is arranged around the outer periphery of the turntable platform 82. The upper portion of the turntable housing 98 is joined to the sides 40, 42, 44, and 46 of the coal hopper 30. The lower portion of the turntable housing 98 extends to the outer periphery of the rotating turntable support 84. The turntable housing 98 is adapted to assist in preventing foreign objects from getting into the area adjacent to the rotating turntable platform 82. Referring to FIG. 6, coal sweeps 96 are attached to the underside of the turntable platform 82 at the outer periphery of the turntable platform 82 and are adapted to remove loose pieces of coal which might get into the area inside of the turntable housing 98 and under the turntable platform 82. The coal sweeps 96 are small, rectangular members which are positioned perpendicular to the turntable platform 82 and extend downwardly from the periphery of the turntable platform 82. The coal sweeps 96 are positioned so that their longitudinal axis is generally parallel to a radius of the turntable platform 82. Referring to FIG. 6, the turntable housing 98 is also provided with a plurality of clean-out openings 99 disposed on the underside of the turntable housing 98. Preferably, there are eight clean-out openings 99, two of which are shown in FIG. 6. The clean-out openings 99 are adapted to be opened for the purpose of cleaning loose coal and debris from inside the turntable housing 98. The clean-out openings 99 are adapted to be used in cooperation with the coal sweeps 96.

Referring to FIGS. 3, 4, and 7, the turntable assembly 22 further includes an air intake pipe 100 extending to the speed reducer 88, by supplying air from the atmosphere to the speed reducer 88. The air intake pipe 100 is adapted to cooperate with oil in the speed reducer 88 to cool the speed reducer 88. The top portion 102

(FIG. 4) of the air intake pipe 100 is curved; the middle portion 104 (FIG. 4) is substantially straight and arranged in a vertical position adjacent to the substantially vertical side 42 of the coal hopper 30 and the lower portion 106 (FIG. 7) of the air intake pipe 100 is curved to facilitate connection to the speed reducer 88. The intake pipe 100 is disposed outside of the coal hopper 30 and has an intake orifice 108 which faces in a downward direction.

Referring to FIG. 6, the turntable assembly 22 further includes a turntable guide 85 which is mounted on the top surface of the turntable platform 82 and is adapted to cooperate with coal guide 34 of the coal hopper assembly 20 to maintain the insulation layer 79. The turntable guide 85 is positioned on the outer circumference of the lower periphery 80 of the coal guide 34 or the turntable guide 85 may be comprised of segments of a circle surrounding the lower periphery 80 of the coal guide 34. In either case, there is a space between the turntable guide 85 and the lower periphery 80 of the coal guide 34 or the turntable guide 85 and the lower periphery 80 of coal guide 34 to allow the turntable guide 85 to rotate around the lower periphery 80 of the coal guide 34.

Lid Lifter Assembly

Referring to FIGS. 10, 11 and 18, the lid lifter assembly 24 is adapted to lift the lid 29 up and off of the charging hole 9 in order to open the charging hole 9 for the charging of coal. The lid lifter assembly 24 swings the lid 29 out of the way prior to the charging of coal through the charging hole 9 into the coke oven 8 and replaces the lid 29 on the charging hole 9 after the charging of coal into the coke oven 8 has been completed. The lid lifter assembly 24 includes an electromagnet assembly 110; a means for moving the electromagnet assembly 110 in a horizontal plane; a means for moving the electromagnet assembly 110 in a vertical plane; and a carriage 112 for supporting the electromagnet assembly 110, the means for moving the electromagnet assembly 110 in a horizontal plane, and the means for moving the electromagnet assembly 110 in a vertical plane.

The electromagnet assembly 110 has a magnetized condition, adapted for attracting the lid 29 and holding the lid 29 while the lid 29 is being lifted up and off of the charging hole 9 and swung out of the way, and a non-magnetized condition adapted for releasing the lid 29 to deposit it on the charging hole 9. Referring to FIGS. 11 and 18, the means for moving the electromagnet assembly 110 in a horizontal plane moves the electromagnet assembly 110 between a work position 113 where the electromagnet 114 is positioned over and in alignment with the charging hole 9 and in alignment with the coal drop assembly 26 and a non-work position 115, shown in FIG. 11 in phantom by dot-dash lines. Referring to FIG. 11, the lid lifter assembly 24 is placed in the work position 113 when it is either removing or replacing a lid 29 on a charging hole 9. The lid lifter assembly 24 is placed in the non-work position either when it has swung a lid 29 out of the way prior to charging coal into a charging hole 9 or when the coal charging car 1 is about to be moved from one coke oven 8 to another coke oven 8, in which case the electromagnet assembly 110 is no longer holding a lid 29 because it has already replaced the lid 29 on the charg-

ing hole 9. Referring to FIG. 10, the means for moving the electromagnet assembly 110 in a vertical plane is brought into operation after the electromagnet 114 is positioned over and in alignment with the lid 29. The means for moving the electromagnet assembly 110 in a vertical plane moves the electromagnet assembly 110 between a raised position, shown in FIG. 10, and a lowered position (not shown).

Referring to FIG. 18, this embodiment of the coal charging car 1 used three separate lid lifter assemblies 24, one lid lifter assembly 2 for each of the three charging holes 9 of a coke oven 8. Other embodiments of the coal charging car 1 may provide a greater or lesser number of lid lifter assemblies for a greater or lesser number of coal charging holes 9. In this embodiment, the electromagnet assembly 110 and other associated components of the lid lifter assembly 24 move in a horizontal plane in an arc 111 of approximately 42°. Other embodiments may be arranged so that the electromagnet assembly 110 moves across a smaller or larger arc.

Referring to FIG. 10, 11, 16 and 17, the electromagnet assembly 110 includes an electromagnet 114, an electromagnet support plate 116, an electrical conductor 118, a gimbal 120, and a gimbal support 122. The electromagnet 114 has a magnetized condition adapted for attracting and grasping the lid 29 of the coke oven 8 while the lid 29 is being lifted off of the charging hole 9 and a nonmagnetized condition adapted for depositing the lid 29 on the charging hole 9. The electromagnet support plate 116 is attached to the electromagnet 114, such as by means of bolts 117. The electrical conductor 118 is connected to the electromagnet 114 through the electromagnet support plate 116 to supply electrical energy to the electromagnet 114 to energize the electromagnet 114 to the magnetized condition and to remove electrical energy to de-energize the electromagnet 114 to the non-magnetized condition. The electromagnet support plate 116 is supported on a gimbal 120. The gimbal support 122 is adapted to support the gimbal 120, the electromagnet support plate 116 and the electromagnet 114. The gimbal support 122 has a gimbal end to which the gimbal 120 is connected and a pantograph guide end. The pantograph guide end of the gimbal support 122 is connected to a pantograph guide 160 and positioned within the pantograph guide 160 which is part of the pantograph assembly. The pantograph guide 160 and the gimbal support 122 are adapted to move in a vertical plane between a raised position, shown in FIG. 10, and a lowered position (not shown).

The gimbal 120 is designed to hold the electromagnet support plate 116 and the electromagnet 114 in a substantially level position at all times. The gimbal 120 is also designed to support the electromagnet 114 and the electromagnet support plate 116 without the electromagnet support plate 116 being fixedly attached to the gimbal 120. This allows the electromagnet support plate 116 and the electromagnet 114 to be oscillated or shaken in a substantially horizontal plane for the purpose of removing carbonaceous material formed during the coking operation from the sealing edge of the lid 29. For this purpose, the gimbal 120 is provided with a plurality of gimbal wheels 121, and preferably three wheels 121. The outer circumference of the magnet support plate 116 is positioned on the gimbal wheels 121, with the gimbal wheels 121 making contact at the

underside of the outer circumference of the electromagnet support plate 116.

Referring to FIGS. 11, 15 and 18, the means for moving the electromagnet 114 in a horizontal plane between the work position 113 and the non-work position 115 includes: a rotating hydraulic cylinder 124, a cylinder rod 126, a rotating crank 128, a rotating mast 130, and a mast support structure 132. The rotating hydraulic cylinder 124 is affixed to the frame 136 of the coal charging car 1 and is adapted to supply power for horizontal movement of the electromagnet 114 between the work position 113 and the non-work position 115. The rotating hydraulic cylinder 124 does not itself rotate, but causes rotation of the electromagnet 114 through an arc of less than a complete circle, such as, 42°. The cylinder rod 126 is adapted for reciprocating motion in a horizontal plane within the rotating hydraulic cylinder 124. The cylinder rod 126 has an interior end disposed within the rotating hydraulic cylinder 124 and an exterior end disposed outside the rotating hydraulic cylinder 124. The exterior end of the cylinder rod 126 is connected to a rotating crank 128 adapted for movement in a horizontal plane. The rotating crank 128 has a cylinder rod end which is connected to the cylinder rod 126 and a mast end which is connected to the mast 130. Crank 128 may be affixed to mast 130 by bolts 133 or crank 128 may be keyed to mast 130. The mast 130 is a cylindrical structural member having a longitudinal axis disposed in a vertical position and adapted for rotation. The upper end of the mast 130 is connected to the mast end of the rotating crank 128. Reciprocating motion of the cylinder rod 126 turns the crank 128 which turns the mast 130. Rotation of the mast 130 moves the electromagnet assembly 110 in a horizontal plane between the work position 113 and the non-work position 115. There is also a mast support structure for supporting the mast 130 on the carriage 112.

Referring to FIG. 15, the mast support structure includes a flange bearing 125, a housing 127 for the flange bearing, a mast support 132, a sleeve bearing 129 and a split bearing housing 131. The flange bearing 125 may be made of bronze and treated with graphite. The housing 127 for the flange bearing 125 is disposed around the mast 130 and includes an oil seal 134. The mast support 132 is disposed around the mast 130 and under the flange bearing housing 127. The sleeve bearing 129 is also disposed around the mast 130 under the mast support 132. The sleeve bearing 129 may be made of bronze and treated with graphite. The split bearing housing 131 is disposed around the sleeve bearing 129 and under the mast support 132.

Referring to FIGS. 10, 11, 12 and 14, the means for moving the electromagnet assembly 110 in a vertical plane includes: a lifting hydraulic cylinder 140; a cylinder rod 142; a lifting crank 144; one or more, and preferably a pair of, pantograph assemblies 146; and a pantograph shaft 148 on which elements of the pantograph assemblies 146 rotate. The lifting hydraulic cylinder 140 is mounted on the carriage 112 and is adapted to supply power for the vertical movement of the electromagnet assembly 110 between a raised position, shown in FIG. 10, and a lowered position, in which the electromagnet 114 is brought in contact with the lid 29. The cylinder rod 142 is adapted for reciprocating motion within the lifting hydraulic cylinder 140. The lifting crank 144 has a cylinder rod end which is con-

nected to the exterior end of the cylinder rod 142 and a pantograph end which is connected to the pantograph assembly 146. The pantograph assembly 146 is connected to the electromagnet assembly 110 and is adapted to maintain the electromagnet assembly 110 in a substantially level configuration during both vertical and horizontal movement of the electromagnet assembly 110 and is adapted to prevent the electromagnet assembly 110 from tilting, particularly when the electromagnet assembly 110 is carrying the lid from the charging hole 9.

Referring to FIGS. 10 and 14, the pantograph assembly 146 includes: an upper pantograph arm 152, a lower pantograph arm 154, a pantograph shaft support 156, a plurality of pantograph shaft braces 158, a pantograph guide 160, and a spring lever arm 161. The upper pantograph arm 152 has a shaft end which is connected to the pantograph shaft 148 and a guide end which is rotatably connected to the pantograph guide 160. The lower pantograph arm 154 has a pantograph support end rotatably connected to the pantograph support 156 and a pantograph guide end rotatably connected to the pantograph guide 160. The pantograph shaft support 156 is mounted on the carriage 112 and is connected and adapted to support the pantograph shaft 148. In this embodiment two pantograph shaft braces 158 are also mounted on the carriage 112 and support the pantograph shaft 148. The pantograph guide 160 is an elongated structural member having a longitudinal axis disposed in a vertical plane and an interior channel 162. The guide end of the upper pantograph arm 152 and the guide end of the lower pantograph arm 154 move the pantograph guide 160 in a vertical plane and thereby move the electromagnet assembly 110 in a vertical plane. Respective points on the upper pantograph arm 152 and the lower pantograph arm 154 are maintained at a constant distance at all times in order to maintain the electromagnet assembly 110 in a level condition without tilting.

Referring to FIGS. 10, 11, 13, 16 and 17, the lid lifter assembly 24 further comprises a lid oscillating assembly for cleaning the lid 29 of the charging hole 9 prior to removal of the lid 29 from the charging hole 9, and for seating the lid 29 snugly in the charging hole 9 when the lid 29 is returned to the charging hole 9 after the charging of coal has been completed. The lid oscillating assembly cleans the lid 29 by oscillating the lid 29, that is, by shaking the lid 29 in a horizontal plane for the purpose of removing carbonaceous material formed during the coking operation from the sealing edge of the lid 29. Referring to FIGS. 10 and 11, the lid oscillating assembly includes: lid oscillating bars 172, a lid oscillating motor 174, a speed reducer 177 for the lid oscillating motor 174, and a means for transmitting power from the lid oscillating motor 174 to the lid oscillating bars 172. There are one or more, and preferably two, lid oscillating bars 172. Referring to FIGS. 16 and 17, each lid oscillating bar 172 is attached to the electromagnet assembly 110 and, more particularly, to the electromagnet support plate 116 by means of an oscillating pin 173. The lid oscillating motor 174 is mounted on the carriage 112 and supplies rotating power through speed reducer 177 to shake the lid oscillating bar 172, which in turn, shakes the electromagnet support plate 116. The design of the electromagnet assembly 110 whereby the electromagnet support plate 116 rides freely upon the gimbal wheels 121, instead,

of being attached to the gimbal 120, allows this shaking action to be transmitted to the lid 29.

Referring to FIGS. 10, 11 and 13, the means for transmitting power from the lid oscillating motor 174 to the lid oscillating bars 172 includes: a shaft 175 of the speed reducer 177, a lid oscillating crank 176 attached to the speed reducer shaft 175, a lid oscillating link 178, and one or more, and preferably two, lid oscillating cables 182. Rods could be used instead of cables 182. One end of each cable 182 is attached to an oscillating bar 172. The rate of rotation of the rotating power from the lid oscillating motor 174 is reduced by the speed reducer 177 which is also mounted on the carriage 112. Referring to FIG. 13, rotation of the speed reducer shaft 175 turns the oscillating crank 176 which moves the oscillating link 178 and causes the cam 180 to oscillate on its pivot point 181 disposed in the approximate midpoint of the cam 180. This oscillating movement of the cam 180 is transmitted to the cables 182, to the oscillating bars 172, and ultimately to the lid 29 through the electromagnet support plate 116 and the electromagnet 114.

The lid lifting assembly 24 further includes an alternate means for raising the electromagnet assembly 110 in a vertical plane in event of emergency, such as malfunction of the primary means for moving the electromagnet assembly 110 in a vertical plane. The primary means is the lifting hydraulic cylinder 140. Referring to FIGS. 10, 11 and 14, the alternate means includes a pair of each of the following elements: an emergency compression spring 184, a spring mounting 186, and a spring compression arm 188. The emergency compression spring 184 is mounted on and wound around a spring mounting 186 supported on the carriage 112. One end of the spring mounting 186 has a spring stop 191 against which the spring 184 abuts. The other end of the spring mounting 186 is attached to the spring compression arm 188. There is an adjustment means 190 to lengthen or shorten the stroke of spring mounting 186 as spring mounting 186 slides through stop 191. This adjustment means 190 allows adjustment of the vertical travel of the gimbal 120. The pantograph end of the compression arm 188 is connected to the pantograph assembly 146 and, more specifically, to the spring lever arm 161 of the pantograph assembly 146.

The operation of the alternate emergency means for raising the electromagnet assembly 110 is as follows. When the lifting hydraulic cylinder 140 operates the pantograph assembly 146 to lower the electromagnet assembly, the spring lever 161 of the pantograph assembly 146 moves the compression arm 188 in a direction which compresses the spring 184, that is, to the left in view shown in FIG. 14. The compression of the spring 184 stores energy which is available in the event of emergency, such as malfunction of the lifting hydraulic cylinder. In event of such emergency, the compression spring 184 can be released to push the compression arm 188 to the right, in the view shown in FIG. 12, which will raise the electromagnet assembly 110. Thus, if the hydraulic system supplying power to the hydraulic lifting cylinder malfunctions, or if the hydraulic lifting cylinder malfunctions, the electromagnet assembly 110 need not be left in its lowered position. The compression spring 184 and its associated elements enables the electromagnet assembly 110 to be raised and, thus, allows the charging car 1 to be moved. If the electromagnet assembly 110 were left in its low-

ered position, the charging car 1 could not be moved because to do so would raise the risk of dragging or bumping the electromagnet assembly 110 on the roof 4 or against some object located on the roof 4, thus damaging the electromagnet assembly 110 and, possibly, other elements of the coal charging car 1.

Referring to FIGS. 4 and 14, the lid lifter assembly is also provided with a heat shield 192. The heat shield 192 is an enclosure disposed around a portion of the lid lifter assembly 24, and, more specifically, around the lid oscillating motor 174 and the lifting hydraulic cylinder 140.

Coal Drop Assembly

Referring to FIGS. 4, 19, 20, 21 and 22, the coal drop assembly 26 comprises an inclined coal section 200 and a substantially vertical coal section 202. The inclined coal section 200 has a longitudinal axis which is inclined at an angle of approximately 45° with reference to the horizontal plane. The inclined coal section 200 is connected at its upper end to the discharge spout 28 of the coal hopper assembly 20. The inclined coal section 200 is adapted to receive coal from the coal hopper assembly 20 through the discharge spout 28 and convey the coal to the substantially vertical coal section 202 on its way to the charging hole 9, shown in FIG. 1 and 19. The inclined coal section 200 allows the coal hopper assembly 20 to be positioned away from and out of alignment with the charging hole 9, shown in FIG. 1, during the charging of coal into the charging hole 9, thereby avoiding exposure of the coal hopper assembly 20 and the turntable assembly 22 to the heat from the charging hole 9. The substantially vertical coal section 202 has a longitudinal axis which is substantially perpendicular to the horizontal plane. The top of the substantially vertical coal section 202 is connected to the bottom of the inclined coal section 200 and is adapted to deliver coal from the inclined coal section 200 to the charging hole 9, shown in FIGS. 1 and 17.

Referring to FIGS. 19 and 20, the substantially vertical coal section 202 of the coal drop assembly 26 includes a stationary coal portion 204 and a movable coal portion 206. The movable coal portion 206 is adapted to telescope in a vertical plane between a raised position and a drop position. As a result, the movable coal portion 206 is adapted to bring the bottom end of the coal drop assembly 26 to a position adjacent to the charging hole 9 of a coke oven 8, shown in FIG. 1, for the delivery of coal to the charging hole 9. The movable coal portion 206 is also adapted to be returned in the direction of arrow 205 in FIG. 19 from the drop position to the raised position when the coal charging car 1, shown in FIG. 1, is to be moved to the next charging hole 9. Referring to FIG. 19, the raised position of the movable coal portion 206 is shown in phantom by dot-dash lines and the drop position of movable coal portion 206 is shown in solid line.

Referring to FIG. 20, the coal drop assembly 26 further comprises a stationary exhaust section 208 adapted to conduct coal gases away from the coal drop assembly 26. Referring to FIGS. 19 and 20, the exhaust section 208 includes a horizontal exhaust portion 210 and a vertical exhaust portion 212. The horizontal exhaust portion 210 is connected to the upper end of the vertical exhaust portion 212 and is disposed at approximately a 90° angle to the vertical exhaust portion 212.

As a result, the horizontal exhaust portion 210 forms an elbow configuration with the vertical portion 66. Referring to FIG. 19, the vertical exhaust portion 212 of the stationary exhaust section 208 is axially disposed around the stationary coal portion 204 of the substantially vertical coal section 202. A part of the vertical exhaust portion 212 is axially disposed within the movable coal portion 206 of the substantially vertical coal section 202. There is a space between the outer vertical portion 212 of the exhaust section 208 and the inner stationary coal portion 204 of the substantially vertical coal section 202. This space forms a stationary exhaust duct 214 between the vertical portion 212 of the exhaust section 208 and the stationary coal portion 204 of the substantially vertical coal section 202.

The movable coal portion 206 of the substantially vertical coal section 202 includes: an outer movable sleeve 216 and an inner movable sleeve 218. The outer movable sleeve 216 of the movable coal portion 206 is axially and slidably disposed outside of and around the vertical exhaust portion 212 of the exhaust section 208. The inner movable sleeve 218 of the movable coal portion 206 is axially and slidably disposed outside of and around the stationary coal portion 204 of the substantially vertical section 202. The movable coal portion 206 has a space between the inner movable sleeve 218 and the vertical exhaust portion 212 of the exhaust section 208. This space forms a transition exhaust duct 220 between the upper portion of the inner movable sleeve 218 of the movable coal portion 206 and the lower portion of the vertical exhaust portion 218 of the exhaust section 208.

The movable coal portion 206 of the substantially vertical section 202 has a space between the inner movable sleeve 218 and the outer movable sleeve 216. This space forms a movable exhaust duct 222 between the inner movable sleeve 218 of the movable portion 206 and the outer movable sleeve 216 of the movable portion 206. Thus, the exhaust system includes: horizontal exhaust portion 210; stationary exhaust duct 214 between vertical exhaust portion 212 and stationary coal portion 204; transition exhaust duct 220 between the upper portion of inner movable sleeve 218 and the lower portion of vertical exhaust portion 212; and movable exhaust duct 222 between inner movable sleeve 218 and outer movable sleeve 216.

The movable exhaust duct 222 leads to the transition exhaust duct 220, then to the stationary exhaust duct 214, then to the upper portion of vertical exhaust portion 212, then to the horizontal portion 210 of the exhaust section 208. The movable exhaust duct 222 is adapted to conduct coal gas from the charging hole 9 to the horizontal exhaust portion 210 of the exhaust section 208. The coal gases travel from charging hole 9 up through movable exhaust duct 222, transition exhaust duct 220 and stationary exhaust duct 214. The movable exhaust duct 222 is adapted to move with the movable coal portion 206 of the substantially vertical coal section 202. The movable exhaust duct 222 is adapted to telescope in a vertical plane from a raised position to a drop position, thereby bringing the bottom end of the movable exhaust duct 222 to a position adjacent to the charging hole 9 of the coke oven.

Referring to FIGS. 3 and 4, the coal drop assembly 26 further includes an exhaust stack 224 adapted to conduct coal gas away from the exhaust section 208. The exhaust stack 224 has a substantially vertical upper

portion 226, an inclined middle portion 228, and a short substantially vertical lower portion 230. Referring to FIG. 19, the vertical lower portion 230 is connected to the horizontal exhaust portion 210 of the stationary exhaust section 208. Referring to FIG. 4, exhaust stack 224 is partially supported by the exhaust stack stabilizer 232.

Referring to FIGS. 19, 21 and 22, the coal drop assembly 26 further includes a means for raising and lowering the movable coal portion 206 in a vertical plane between its raised position and its drop position. Referring to FIGS. 19 and 21, the means includes a coal drop hydraulic cylinder 238, a coal drop crank mechanism 240, a coal drop counterweight 242, and a coal drop linkage means. Preferably, a pair of linkage means are used, one linkage means disposed on each side of the coal drop assembly. Each linkage means of the pair includes an upper bar 246, a coal drop lever 248, a lower bar 250, and an adjustable linkage means connecting the lower bar 250 to the movable coal portion 206.

The coal drop cylinder 238 is a hydraulic cylinder having a cylinder rod 239 adapted for reciprocation therein. The cylinder rod 239 has an interior end disposed within the hydraulic cylinder 238 and an exterior end connected to the coal drop crank mechanism 240. The crank mechanism 240 is adapted to rotate upon actuation by the cylinder rod 239 and is adapted to raise and lower the linkage means, the counterweight 242 and the movable coal portion 206. The direction in which the crank mechanism 240 moves to lower these elements is indicated by arrows 237 and 241. Preferably, each of the pair of upper bars 246 is divided into two parts and connected by an upper bar turnbuckle 254. Similarly, each of the lower bars 250 is divided into two parts and connected by a lower bar turnbuckle 256. The turnbuckles 254 and 256 merely allow adjustment of the length of the upper and lower bars 246 and 250. The upper end of each of the upper bars 246 is connected to the coal drop crank 242. The lower end of each of the upper bars 246 is connected to the upper bar end of the coal drop lever 248, which is also the counterweight end of the coal drop lever 248, and to a counterweight bar 258 by means of an upper bar link 259. The counterweight bar 258 is connected to the counterweight 242. The opposite lower bar end of the coal drop lever 248 is connected to the lower bar 250 by means of a lower bar link 251. The coal drop lever 248 is rotatably fixed to the coal drop assembly 26 and has a pivot point 247 in the approximate center of the coal drop lever 248 upon which pivot point 247 the lever 248 rotates. The lower bar 250 is connected to an adjustable link 252 which is connected to a movable coal portion link 260 which is connected to the movable coal portion 206.

Referring to FIG. 19, the counterweight 242 provides a balancing effect during movement of the movable coal portion 206. When the movable coal portion 206 is being raised, the counterweight 242 is lowered. Conversely, when the movable coal portion 206 is being lowered to its drop position, the counterweight is raised. The raised position of the counterweight 242 is shown in solid line and the lowered position of the counterweight is shown in phantom by dot-dash lines. Downward movement of the counterweight 242 is indicated by the arrow 243. Corresponding movement of coal drop lever 248 is indicated by arrow 249 in FIG. 19. When the counterweight end of the coal drop lever

248 is moving down, the lower bar end of the coal drop lever 248 is moving up. Each coal drop lever 248 has a pivot point 247 in approximately the middle of the coal drop lever 248.

Referring to FIG. 21, one linkage means is disposed on each side of the coal drop assembly 26. Referring to FIG. 22, the coal drop assembly 226 may be supported by an optional coal drop support 253 affixed to the frame 255 of the charging car 1. One end of the coal drop support 253 is affixed to the frame 255 of the charging car 1 and the other end of which is affixed to a portion of the coal drop assembly 26 such as inclined coal section 200.

Referring to FIGS. 19 and 21, the coal drop assembly 26 further includes a clean-out opening 234 positioned on the outlet side of the horizontal exhaust portion 210 of stationary exhaust section 208. Referring to FIG. 19, clean-out opening 234 is positioned to the right of the lower portion 230 of the exhaust stack 224. The clean-out opening 234 may be opened to allow the stationary exhaust section 208 to be cleaned out.

Referring to FIG. 19, the coal drop assembly 26 further includes an access plate 236 located on the upper side of the inclined coal section 200. The access plate 236 may be opened to facilitate access into the coal drop assembly 26.

Additional Assemblies

Referring to FIGS. 2, 3 and 4, the coal charging car 1 of this invention further includes a traction drive assembly 268, an operator's control cabin 270, an electrical control cabin 272, an electrical resistor cabinet 274, dual hydraulic pumps 278, and a trolley support 276.

The electrical resistor cabinet 274 houses the various resistors required for the electrical system of the coal charging car 1. The electrical control cabin 272 houses the electrical controls for the coal charging car 1. The electrical control cabin 272 is insulated and air conditioned and has hatch-type doors. Referring to FIGS. 1, 2 and 4, the traction drive assembly 268 provides the power for moving the coal charging car 1 of this invention by means of a plurality of traction wheels 269 and 271 on the rails 18. Preferably, four traction wheels 269 and four trailer wheels 271 are used, four wheels 269 and 271 on each side of the coal charging car 1. The rear traction wheels 269 are driven by the traction drive assembly 268; the front trailer wheels 271 are not. Referring to FIG. 2, the operator's control cabin 270 provides a compartment from which an operator runs the coal charging car 1. Referring to FIG. 3, the dual hydraulic pumps 278 provide power to operate the hydraulic equipment, including the lifting hydraulic cylinder 140, the rotating hydraulic cylinder 124 of the lid lifting assembly 24, and the coal drop hydraulic cylinder 238.

The coal charging car 1 is also provided with a pressurized lubrication system for lubricating various moving elements and a safety limit system to interrupt operation of a coal charging car 1 in event of malfunction. The coal charging car 1 includes a support frame 280 upon which the coal hopper assembly 20, the turntable assembly 22, the lid lifter assembly 24 and the coal drop assembly 26 are mounted.

We claim:

1. A coal charging car adapted for conveying coal to a coke oven having a lid on a charging hole, said charg-

ing hole having heat emanating therefrom when the coke oven is in operation, said coal charging car in combination comprising:

a coal hopper assembly which receives coal from a coal supply source;
a turntable assembly disposed below said coal hopper assembly, said turntable assembly being adapted to cooperate in dispensing coal from said coal hopper assembly;

means for displacing said turntable assembly and said coal hopper assembly from said charging hole when coal is being charged into said charging hole, thereby avoiding exposure of said turntable assembly to the heat from said charging hole;

a lid lifter assembly disposed adjacent to said coal hopper assembly, said lid lifter assembly being adapted to remove said lid from said charging hole of said coke oven, prior to the charging of coal into said charging hole;

a coal drop assembly connected to and disposed below said coal hopper assembly, said coal drop assembly being adapted to deliver coal from said coal hopper assembly to said charging hole of said coke oven, said displacing means comprising: an inclined coal section of said coal drop assembly, the longitudinal axis of which is inclined at an angle

with reference to the horizontal plane, said inclined coal section having a length which exceeds the maximum width within said coal drop assembly and being connected to said coal hopper assembly, said inclined coal section being adapted to receive coal from said coal hopper assembly, and said length of said inclined section substantially displacing said coal hopper assembly and said turntable assembly from and out of vertical alignment with the charging hole during the charging of coal into the charging hole, thereby avoiding exposure of said coal hopper assembly and said turntable assembly to the heat from said charging hole, said substantial displacement resulting from said length of said inclined coal section.

2. The coal charging car according to claim 1 wherein: said turntable assembly comprises a rotatable turntable platform, a rotatable platform support, and a speed reducer, said platform support extending substantially under the entire turntable platform to provide support for said turntable platform; said platform support and said speed reducer, as parts of said turntable assembly, being disposed from and out of vertical alignment with said charging hole when coal is being charged into said charging hole, thereby avoiding exposure of said turntable platform, platform support and speed reducer to the heat from said charging hole.

3. The coal charging car according to claim 2 wherein said turntable assembly further comprises an air intake pipe extending to said speed reducer of said turntable assembly, said air intake pipe being adapted to cooperate in cooling said speed reducer.

4. The coal charging car according to claim 1 wherein said coal hopper assembly comprises: a coal hopper having a partial funnel shape at the bottom portion of said coal hopper; a discharge spout at the bottom of said coal hopper through which discharge spout coal passes on its way to said charging hole; a deflector disposed in said coal hopper and adapted to deflect coal from said coal hopper into said discharge spout; and a coal guide disposed within said coal hopper over

said turntable assembly and adapted to guide coal on to said turntable assembly.

5. The coal charging car according to claim 1 and further comprising means for retaining an insulation layer in the bottom of said coal hopper assembly, between said coal hopper assembly and said turntable assembly, said insulation layer insulating said turntable assembly from the heat emanating from said coke oven.

6. The coal hopper assembly according to claim 5 wherein said insulation layer comprises a layer of coal.

7. The coal charging car according to claim 1 wherein said turntable assembly comprises: a rotatable turntable platform which is substantially circular in shape and which is disposed beneath said coal hopper assembly; and a rotatable platform support which is disposed below said turntable platform and which supports said turntable platform, said turntable platform being substantially circular in shape, the diameter of said platform support approaching the diameter of said turntable platform; said turntable platform and said platform support, as parts of said turntable assembly, being displaced from and out of vertical alignment with said charging hole when coal is being charged into said charging hole, thereby avoiding exposure of said turntable platform and platform support to the heat from said charging hole.

8. The coal charging car according to claim 7 wherein the platform support extends substantially under the entire turntable platform to provide substantially complete support of said turntable platform and to reduce warpage of said turntable platform.

9. The coal charging car according to claim 7 wherein said turntable assembly further comprises: a drive motor adapted to supply rotating power to rotate said turntable platform; a speed reducer connected to said drive motor and adapted to reduce the speed of the rotating power supplied from said drive motor; and a support coupling disposed beneath and connected to said turntable support, said support coupling being adapted to transmit power from said speed reducer to said turntable support, said drive motor and said speed reducer being arranged right side up under said coal hopper assembly and under said turntable assembly.

10. The coal charging car according to claim 1 wherein said lid lifter assembly comprises: an electromagnet assembly adapted to attract and hold said lid of said charging hole; a means for moving said electromagnet assembly in a horizontal plane between a work position and a non-work position; a primary means for moving said electromagnet assembly in a vertical plane between a raised position and a lowered position, and a carriage for supporting said electromagnet assembly, said means for moving said electromagnet assembly in a horizontal plane, and said primary means for moving said electromagnet assembly in said vertical plane, said means for moving said electromagnet assembly in a horizontal plane and said means for moving said electromagnet assembly in said vertical plane being displaced from and out of vertical alignment with said charging hole when coal is being charged into said charging hole, thereby avoiding exposure of said means for moving said electromagnet assembly in a horizontal plane and said means for moving said electromagnet assembly in said vertical plane to the heat from said charging hole.

11. The coal charging car according to claim 10 wherein said electromagnet assembly comprises: an

electromagnet having a magnetized condition adapted for attracting and grasping said lid while said lid is being lifted off of said charging hole and a non-magnetized condition; an electromagnet support plate to which said electromagnet is attached; an electrical conductor connected to said electromagnet and adapted to energize said electromagnet to a magnetized condition and de-energize said electromagnet to a non-magnetized condition; a gimbal in which said electromagnet support plate is mounted; and a gimbal support, adapted to support said gimbal, electromagnet support plate and electromagnet.

12. The coal charging car according to claim 10 wherein said means for moving said electromagnet assembly in said horizontal plane comprises: a rotating hydraulic cylinder adapted to supply power for horizontal movement of said electromagnet assembly; a cylinder rod for said horizontal movement, said cylinder rod being adapted for reciprocating motion within said rotating hydraulic cylinder and having an exterior end disposed outside of said rotating hydraulic cylinder; a rotating crank adapted for movement in a horizontal plane, said rotating crank having a cylinder rod end and a mast end, said cylinder rod end of said crank being connected to said exterior end of said cylinder rod; a rotating mast disposed in a vertical position, the upper end of said mast being connected to said mast end of said rotating crank, whereby the reciprocating motion of said cylinder rod turns said crank, which turns said mast, which moves said electromagnet assembly in a horizontal plane between a work position and a non-work position; and a mast support structure supporting said mast on said carriage.

13. The coal charging car according to claim 10 wherein said lid lifter assembly further comprises a lid oscillating assembly for cleaning said lid of said charging hole, said lid oscillating assembly comprising: a lid oscillating bar attached to said electromagnet assembly, said lid oscillating bar being adapted to shake said lid for the purpose of removing carbonaceous material from said lid; a lid oscillating motor adapted to supply power to said lid oscillating bar; and a means for transmitting power from said lid oscillating motor to said lid oscillating bar.

14. The coal charging car according to claim 10 wherein said primary means for moving said electromagnet assembly in a vertical plane comprises: a lifting hydraulic cylinder for supplying power for said vertical movement of said electromagnet assembly; a cylinder rod for said vertical movement, said cylinder rod being adapted for reciprocating motion within said lifting hydraulic cylinder and having an exterior end disposed outside of said lifting hydraulic cylinder; a lifting crank adapted for movement in a vertical plane, said lifting crank having a piston rod end which is connected to said piston rod; a pantograph assembly connected to said electromagnet assembly and adapted to maintain said electromagnet assembly in a substantially level configuration during movement; and a pantograph shaft on which elements of said pantograph assembly rotate; said lifting hydraulic cylinder, said cylinder rod, said lifting crank, said pantograph assembly and said pantograph rod being displaced from and out of vertical alignment with said charging hole when coal is being charged into said charging hole, thereby avoiding exposure to the heat from said charging hole.

15. The coal charging car according to claim 14 and further comprising alternate means for raising the electromagnet assembly, said alternate means comprising: a compression spring, a spring mounting around which said compression spring is mounted; and a compressor arm having a spring mounting end and a pantograph end, the spring end being connected to the compression spring, the pantograph end being connected to said pantograph assembly.

16. The coal charging car according to claim 1 wherein said coal drop assembly further comprises: a substantially vertical coal section, the longitudinal axis of which is substantially perpendicular to the horizontal plane, said substantially vertical coal section being connected to said inclined coal section and being adapted to deliver coal from said inclined coal section to said charging hole.

17. The coal charging car according to claim 16 wherein said substantially vertical coal section comprises a stationary coal portion and a movable coal portion, said movable coal portion being adapted to telescope in a vertical plane between a raised position and a drop position, said movable coal portion thereby being adapted to bring the bottom end of said coal drop assembly to a position adjacent to said charging hole of said coke oven for the delivery of coal to said charging hole, and said movable coal portion being adapted to be returned from said coal drop position to said raised position.

18. The coal charging car according to claim 17 and further comprising a means for moving said movable coal portion in a vertical plane between a raised position and a drop position, said means comprising: a coal drop hydraulic cylinder adapted to supply power to raise and lower said movable coal portion; a cylinder rod adapted to reciprocate within said coal drop hydraulic cylinder, said cylinder rod having an interior end disposed within said cylinder and an exterior end disposed outside said cylinder; a cylinder crank mechanism to which the exterior end of said cylinder rod is attached; a coal drop counterweight which provides a balancing effect during movement of said movable coal portion; and a coal drop linkage means adapted to link said coal drop crank mechanism to said movable coal portion and transfer power from said hydraulic cylinder to said movable coal portion.

19. The coal charging car according to claim 17 and further comprising an exhaust section adapted to conduct coal gases away from said coal drop assembly.

20. The coal charging car according to claim 19 wherein said exhaust section comprises: a horizontal exhaust portion and a vertical exhaust portion; said horizontal exhaust portion being disposed at approximately a 90° angle to said vertical exhaust portion, said horizontal exhaust portion thereby forming an elbow configuration with said vertical exhaust portion, said vertical exhaust portion of said exhaust section being axially disposed around said stationary coal portion of said substantially vertical coal section and having a space between said outer vertical portion of said exhaust section and said linear stationary coal portion of said substantially vertical coal section, said space forming a stationary exhaust duct between the vertical portion of said exhaust section and the stationary coal portion of said substantially vertical coal section.

21. The coal charging car according to claim 19 wherein said coal drop assembly further comprises an

exhaust stack connected to said exhaust section, said exhaust stack being adapted to conduct coal gas away from said exhaust section.

22. A coal charging car adapted for conveying coal to a coke oven, lifting a lid from a charging hold on said coke oven and charging coal into said charging hole of said coke oven, said charging hole having heat emanating therefrom when the coke oven is in operation, said coal charging car in combination comprising: a coal hopper assembly which receives coal from a coal supply source; a turntable assembly disposed below said coal hopper assembly, said turntable assembly being adapted to dispense coal from said coal hopper assembly, said turntable assembly and said coal hopper assembly being out of alignment with said charging hole when coal is being charged into said charging hole, thereby avoiding exposure of said turntable assembly to the heat from said charging hole; a lid lifter assembly disposed adjacent to said coal hopper assembly, said lid lifter assembly being adapted to lift said lid up from said charging hole of said coke oven, swing said lid out of the way prior to the charging of coal into said charging hold of said coke oven and replace said lid on said charging hole of said coke oven after said charging; and a coal drop assembly connected to and disposed below said coal hopper assembly, said coal drop assembly being adapted to deliver coal from said coal hopper assembly to said charging hole of said coke oven;

wherein said coal hopper assembly comprises: a coal hopper having a partial funnel shape at the bottom portion of said coal hopper; a discharge spout at the bottom of said coal hopper through which discharge spout coal passes on its way to said charging hole; a deflector disposed in said coal hopper and adapted to deflect coal from said coal hopper into said discharge spout; a coal guide disposed within said coal hopper over said turntable assembly and adapted to guide coal on to said turntable assembly; and an insulation layer of coal disposed in the bottom of said coal hopper assembly, said insulation layer being adapted to insulate said turntable assembly from the heat from said coke oven;

wherein said turntable assembly comprises: a turntable platform which is substantially circular in shape and which is disposed beneath said coal hopper assembly; a turntable support which is disposed below said turntable platform and which supports said turntable platform, said turntable platform being substantially circular in shape, the diameter of said turntable support approaching the diameter of said turntable platform, said turntable support extending substantially under the entire turntable platform to provide substantially complete support of said turntable platform and to reduce warpage of said turntable platform, a turntable motor and speed reducer for supplying rotating power to said turntable assembly; and an air intake pipe extending to said speed reducer of said turntable assembly, said air intake pipe being adapted to cooperate in cooling said speed reducer;

wherein said lid lifter assembly comprises: an electromagnet assembly adapted to attract and hold said lid of said charging hole; a means for moving said electromagnet assembly in a horizontal plane between a work position and a non-work position; a primary means for moving said electromagnet assembly in a vertical plane between a raised position

and a lowered position; a carriage for supporting said electromagnet assembly, said means for moving said electromagnet assembly in a horizontal plane, and said means for moving said electromagnet assembly in said vertical plane; a lid oscillating assembly for cleaning said lid of said charging hold, said lid oscillating assembly comprising: a lid oscillating assembly for cleaning said lid of said charging hole, said lid oscillating assembly comprises: a lid oscillating bar attached to said electromagnet assembly, said lid oscillating bar being adapted to shake said lid prior to removal from said charging hole for the purpose of removing carbonaceous material from said lid; a lid oscillating motor adapted to supply power to said lid oscillating bar; and a means for transmitting power from said lid oscillating motor to said lid oscillating bar; and wherein said coal drop assembly comprises: an inclined coal section, the longitudinal axis of which is inclined at an angle with reference to the horizontal plane, said inclined coal section being adapted to receive coal from said coal hopper assembly, and said inclined section being adapted to allow said coal hopper assembly to be displaced from and out of alignment with the charging hole during the charging of coal into the charging hole, thereby avoiding exposure of said coal hopper assembly and said turntable assembly to the heat from said charging hole; a substantially vertical coal section, the longitudinal axis of which is substantially perpendicular to the horizontal plane, said substantially vertical coal section being connected to said inclined coal section and being adapted to deliver coal from said inclined coal section to said charging hole, said substantially vertical coal section comprising a stationary coal portion and a movable coal portion, said movable coal portion being adapted to telescope in a vertical plane between a raised position and a drop position, said movable coal portion thereby being adapted to bring the bottom end of said coal drop assembly to a position adjacent to said charging hole of said coke oven for the delivery of coal to said charging hole, and said movable coal portion being adapted to be returned from said drop position to said raised position.

23. A coal charging car adapted for conveying coal to a coke oven having a lid on a charging hole, said charging hole having heat emanating therefrom when the coke oven is in operation, said coal charging car in combination comprising:

a coal hopper assembly which receives coal from a coal supply source; a turntable assembly disposed below said coal hopper assembly, said turntable assembly being adapted to cooperate in dispensing coal from said coal hopper assembly, said turntable assembly and said coal hopper assembly being displaced from said charging hole when coal is being charged into said charging hole, thereby avoiding exposure of said turntable assembly to the heat from said charging hole; a lid lifter assembly disposed adjacent to said coal hopper assembly, said lid lifter assembly being adapted to remove said lid from said charging hole of said coke oven prior to the charging of coal into said charging hole; and

a coal drop assembly connected to and disposed below said coal hopper assembly, said coal drop assembly being adapted to deliver coal from said coal hopper assembly to said charging hole of said coke oven;

wherein said lid lifter assembly comprises: an electromagnet assembly adapted to attract and hold said lid of said charging hole; a means for moving said electromagnetic assembly in a horizontal plane between a work position and a non-work position; a primary means for moving said electromagnet assembly in a vertical plane between a raised position and a lowered position; and a carriage for supporting said electromagnet assembly, said means for moving said electromagnet assembly in a horizontal plane, and said means for moving said electromagnet assembly in said vertical plane;

wherein said lid lifter assembly further comprises a lid oscillating assembly for cleaning said lid of said charging hole, said lid oscillating assembly comprising: a lid oscillating bar attached to said electromagnet assembly, said lid oscillating bar being adapted to shake said lid for the purpose of removing carbonaceous material from said lid; a lid oscillating motor adapted to supply power to said lid oscillating bar; and a means for transmitting power from said lid oscillating motor to said lid oscillating bar; and

wherein said lid oscillating assembly has two lid oscillation bars, said lid oscillating motor has a speed reducer and a speed reducer shaft; and said means for transmitting said power from said lid oscillating motor to said lid oscillating bars comprises: a lid oscillating crank attached at one end to the shaft of said speed reducer; a lid oscillating link having a cam end, said crank end of said link being attached to said crank; a lid oscillating cam having a pivot point in the approximate midportion of said cam, one end of said cam being attached to said crank; and a pair of lid oscillating cables, one end of each cable being attached to opposing ends of said cam and the other end of each cable being attached to said lid oscillating bars.

24. A coal charging car adapted for conveying coal to a coke oven having a lid on a charging hole, said charging hole having heat emanating therefrom when the coke oven is in operation, said coal charging car in combination comprising:

a coal hopper assembly which receives coal from a coal supply source;

a turntable assembly disposed below said coal hopper assembly, said turntable assembly being adapted to cooperate in dispensing coal from said coal hopper assembly, said turntable assembly and said coal hopper assembly being displaced from said charging hole when coal is being charged into said charging hole, thereby avoiding exposure of said turntable assembly to the heat from said charging hole;

a lid lifter assembly disposed adjacent to said coal hopper assembly, said lid lifter assembly being adapted to remove said lid from said charging hole of said coke oven, prior to the charging of coal into said charging hole; and

a coal drop assembly connected to and disposed below said coal hopper assembly, said coal drop assembly being adapted to deliver coal from said coal

drop assembly to said charging hole of said coke oven;

wherein said coal drop assembly comprises: an inclined coal section, the longitudinal axis of which is inclined at an angle with reference to the horizontal plane, said inclined section being connected to said coal hopper assembly, said inclined coal section being adapted to receive coal from said coal hopper assembly, and said inclined section being adapted to allow said coal hopper assembly to be displaced from and out of alignment with the charging hole during the charging of coal into the charging hole, thereby avoiding exposure of said coal hopper assembly and said turntable assembly to the heat from said charging hole; and a substantially vertical coal section, the longitudinal axis of which is substantially perpendicular to the horizontal plane, said substantially vertical coal section being connected to said inclined coal section and being adapted to deliver coal from said inclined coal section to said charging hole;

wherein said substantially vertical coal section comprises a stationary coal portion and a movable coal portion, said movable coal portion being adapted to telescope in a vertical plane between a raised position and a drop position, said movable coal portion thereby being adapted to bring the bottom end of said coal drop assembly to a position adjacent to said charging hole of said coke oven for the delivery of coal to said charging hole, and said movable coal portion being adapted to be returned from said coal drop position to said raised position; said substantially vertical coal section further comprising an exhaust section adapted to conduct coal gases away from said coal drop assembly;

wherein said exhaust section comprises: a horizontal exhaust portion and a vertical exhaust portion; said horizontal exhaust portion being disposed at approximately a 90° angle to said vertical exhaust portion, said horizontal exhaust portion thereby forming an elbow configuration with said vertical exhaust portion, said vertical exhaust portion of said exhaust section being axially disposed around said stationary coal portion of said substantially vertical coal section and having a space between said outer vertical portion of said exhaust section and said inner stationary coal portion of said substantially vertical coal section, said space forming a stationary exhaust duct between the vertical portion of said exhaust section and the stationary coal portion of said substantially vertical coal section; and

wherein said movable coal portion of said substantially vertical coal section of said coal drop assembly comprises: an outer movable sleeve and an inner movable sleeve; said outer movable sleeve of said movable coal portion being axially and slideably disposed outside of and around said vertical portion of said exhaust section; said inner movable sleeve of said vertical exhaust portion of said exhaust section, and said inner movable sleeve of said movable coal portion being axially and slideably disposed outside of and around said stationary coal portion of said substantially vertical section of said coal drop assembly; said movable coal portion having a space between said inner movable sleeve and said vertical exhaust portion of said exhaust sec-

tion, said space forming a transition exhaust duct between the inner movable sleeve of said movable coal portion and the vertical exhaust portion of said exhaust section, said movable coal portion having a space between said inner movable sleeve 5 and said outer movable sleeve, said space forming a movable exhaust duct between said inner movable sleeve of said movable portion and said outer movable sleeve of said movable portion; said movable exhaust duct leading to said horizontal portion 10 of said exhaust section, said movable exhaust duct being adapted to conduct coal gas and combustion gas from said charging hole to said horizontal exhaust portion of said exhaust section, said movable exhaust duct being adapted to move with said movable coal portion of said coal drop assembly and being adapted to telescope in a vertical plane from 15 a raised position to a drop position, thereby bringing the bottom end of said movable exhaust duct to a position adjacent to the charging hole of said 20 coke oven.

25. A coal charging car adapted for conveying coal to a coke oven having a lid on a charging hole, said charging hole having heat emanating therefrom when the coke oven is in operation, said coal charging car in 25 combination comprising:

a coal hopper assembly which receives coal from a coal supply source;

a turntable assembly disposed below said coal hopper assembly, said turntable assembly being adapted to 30 cooperate in dispensing coal from said coal hopper assembly, said turntable assembly and said coal hopper assembly being displaced from said charging hole when coal is being charged into said charging hole, thereby avoiding exposure of said turntable assembly to the heat from said charging hole;

a lid lifter assembly disposed adjacent to said coal hopper assembly, said lid lifter assembly being adapted to remove said lid from said charging hole 35 of said coke oven, prior to the charging of coal into said charging hole; and

a coal drop assembly connected to and disposed below said coal hopper assembly, said coal drop assembly being adapted to deliver coal from said coal hopper assembly to said charging hole of said coke oven; wherein: 40

said coal drop assembly comprises: an inclined coal section, the longitudinal axis of which is inclined at an angle with reference to the horizontal plane, said inclined coal section being connected to said coal hopper assembly, said inclined coal section being adapted to receive coal from said coal hopper assembly, and said inclined section being adapted to allow said coal hopper assembly and said turntable assembly to be displaced from and 45 out of vertical alignment with the charging hole during the charging of coal into the charging hole, thereby avoiding exposure of said coal hopper assembly and said turntable assembly to the heat from said charging hole;

said lid lifter assembly comprises: an electromagnet assembly adapted to attract and hold said lid of said charging hole; a means for moving said electromagnet assembly in a horizontal plane between a work position and a non-work position; a primary means for moving said electromagnet assembly in a vertical plane between a raised position and a lowered position; and a carriage for supporting said electro-

magnet assembly, said means for moving said electromagnet assembly in a horizontal plane, and said primary means for moving said electromagnet assembly in said vertical plane; said means for moving said electromagnet assembly in a horizontal plane and said means for moving said electromagnet assembly in said vertical plane being displaced from and out of vertical alignment with said charging hole when coal is being charged into said charging hole, thereby avoiding exposure of said means for moving said electromagnet assembly in a horizontal plane and said means for moving said electromagnet assembly in said vertical plane to the heat from said charging hole;

said primary means for moving said electromagnet assembly in a vertical plane comprises: a lifting hydraulic cylinder for supplying power for said vertical movement of said electromagnet assembly; a cylinder rod for said vertical movement, said cylinder rod being adapted for reciprocating motion within said lifting hydraulic cylinder and having an exterior end disposed outside of said lifting hydraulic cylinder; a lifting crank adapted for movement in a vertical plane, said lifting crank having a piston rod end which is connected to said piston rod; a pantograph assembly connected to said electromagnet assembly and adapted to maintain said electromagnet assembly in a substantially level configuration during movement; and a pantograph shaft on which elements of said pantograph assembly rotate; said lifting hydraulic cylinder, said cylinder rod, said lifting crank, said pantograph assembly and said pantograph rod being displaced from and out of vertical alignment with said charging hole, when coal is being charged into said charging hole, thereby avoiding exposure to the heat from said charging hole; and

said pantograph assembly comprises: an upper pantograph arm having a pantograph shaft end and a pantograph guide and; a lower pantograph arm having a pantograph support end and a pantograph guide end; a pantograph shaft support for supporting said pantograph shaft on said carriage, said pantograph support end of said lower pantograph arm being rotatably connected to said pantograph shaft support; a plurality of pantograph shaft braces for supporting the pantograph shaft on said carriage; a pantograph guide attached to said guide end of said upper pantograph arm, said guide end of said lower pantograph arm and said electromagnet assembly, for moving said electromagnet assembly in a vertical plane.

26. A coal charging car adapted for conveying coal to a coke oven having a lid on a charging hole, said charging hole having heat emanating therefrom when the coke oven is in operation, said coal charging car in combination comprising:

a coal hopper assembly which receives coal from a coal supply source;

a turntable assembly disposed below said coal hopper assembly, said turntable assembly being adapted to cooperate in dispensing coal from said coal hopper assembly, said turntable assembly and said coal hopper assembly being displaced from said charging hole when coal is being charged into said charging hole, thereby avoiding exposure of said turntable assembly to the heat from said charging hole;

a lid lifter assembly disposed adjacent to said coal hopper assembly, said lid lifter assembly being adapted to remove said lid from said charging hole of said coke oven, prior to the charging of coal into said charging hole; and 5

a coal drop assembly connected to and disposed below said coal hopper assembly, said coal drop assembly being adapted to deliver coal from said coal hopper assembly to said charging hole of said coke oven; wherein: 10

said coal drop assembly comprises: an inclined coal section, the longitudinal axis of which is inclined at an angle with reference to the horizontal plane, said inclined coal section being connected to said coal hopper assembly, said inclined coal section being adapted to receive coal from said coal hopper assembly, and said inclined section being adapted to allow said coal hopper assembly and said turntable assembly to be displaced from and out of vertical alignment with the charging hole 15 during the charging of coal into the charging hole, thereby avoiding exposure of said coal hopper assembly and said turntable assembly to the heat from said charging hole; 20

said coal drop assembly further comprises: a substantially vertical coal section, the longitudinal axis of which is substantially perpendicular to the horizontal plane, said substantially vertical coal section being connected to said inclined coal section and being adapted to deliver coal from said inclined 25 coal section to said charging hole;

said substantially vertical coal section comprises: a stationary coal portion and a movable coal portion, said movable coal portion being adapted to telescope in a vertical plane between a raised position 30 and a drop position, said movable coal portion thereby being adapted to bring the bottom end of said coal drop assembly to a position adjacent to said charging hole of said coke oven for the delivery of coal to said charging hole, and said movable 35

coal portion being adapted to be returned from said coal drop position to said raised position; said coal drop assembly further comprises: a means for moving said movable coal portion in a vertical plane between a raised position and a drop position, said means comprising: a coal drop hydraulic cylinder adapted to supply power to raise and lower said movable coal portion; a cylinder rod adapted to reciprocate within said coal drop hydraulic cylinder, said cylinder rod having an interior end disposed within said cylinder and an exterior end disposed outside said cylinder; a cylinder crank mechanism to which the exterior end of said cylinder rod is attached; a coal drop counterweight which provides a balancing effect during movement of said movable coal portion; and a coal drop linkage means adapted to link said coal drop crank mechanism to said movable coal portion and transfer power from said hydraulic cylinder to said movable coal portion; and

said coal drop assembly further comprises: a pair of said linkage means, each linkage means having an upper bar having an upper end and a lower end, said upper end being connected to said crank mechanism; a coal drop lever having an upper bar end, a lower bar end and a pivot point in the approximate center of said lever upon which pivot point said lever rotates, said upper bar end being connected to said upper bar; a lower bar having an upper end and a lower end, said upper end being connected to said lower bar end of said coal drop lever; an adjustable linkage means having an upper end connected to said lower end of said lower bar and a lower end connected to said movable coal portion; and a counterweight bar having a lower end connected to said counterweight and an upper end connected to said upper bar end of said coal drop level.

UNITED STATES PATENT AND TRADEMARK OFFICE
CERTIFICATE OF CORRECTION

PATENT NO. : 3,910,431

DATED : October 7, 1975

INVENTOR(S) : Homer Donald Fuller and James Arthur Little

It is certified that error appears in the above-identified patent and that said Letters Patent are hereby corrected as shown below:

Col. 3, line 53 - "has" should be "had"

Col. 3, line 65 - there should be no parenthesis after the word assembly

Col. 8, line 45 - "asemby" should be "assembly"

Col. 9, line 3 - "elecromagnet" should be "electromagnet"

Col. 9, line 5 - the word "is" should be deleted

Col. 9, line 10 - "used" should be "uses"

Col. 11, line 49 - "caarbonaceous" should be "carbonaceous"

Col. 14, line 21 - "porton" should be "portion"

Col. 16, line 7 - Figure "226" should be "26"
